[57] CLAIM

The ornamental design for a precision adjustable router fence, as shown.

DESCRIPTION

FIG. 1 is a top, front and right isometric view of a precision adjustable router fence showing my new design;

FIG. 2 is a top plan view;

FIG. 3 is a right side elevational view, that is also a mirror image of a left side elevational view;

FIG. 4 is a bottom plan view;

FIG. 5 is a front elevational view; and,

FIG. 6 is a rear elevational view thereof.

FIG. 1

FIG. 2

FIG. 3

FIG. 4

FIG. 5

FIG. 6
